(57) CLAIM

The ornamental design for a cosmetic bag, as shown and described.

DESCRIPTION

FIG. 1 is a first perspective view of a cosmetic bag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the cosmetic bag thereof;

FIG. 10 is a perspective view of another state of the cosmetic bag thereof; and,

FIG. 11 is a perspective view of another state of the cosmetic bag thereof.

The broken lines shown in the drawings depict portions of the cosmetic bag that form no part of the claimed design.

1 Claim, 11 Drawing Sheets
